FIG. 16

FIG. 17

FIG. 18

FIG. 19

FIG. 1 is a perspective view of a pocket flashlight, showing my new design shown with the head of the light in a tilted position;

FIG. 2 is a perspective view of my novel design with the head of the light in a vertical position;

FIG. 3 is a top elevation thereof with the head of the light in the closed position;

FIG. 4 is a front elevation thereof with the head of the light in the closed position;

FIG. 5 is a left side elevation thereof;

FIG. 6 is a right side elevation thereof;

FIG. 7 is a bottom elevation thereof;

FIG. 8 is a perspective view of a second embodiment of my novel design showing the head of the light in a horizontal position;

FIG. 9 is a perspective view of the embodiment of FIG. 8 showing the head of the light in a vertical position;

FIG. 10 is a front elevation thereof with the head of the light in the closed position;

FIG. 11 is a left side elevation thereof;

FIG. 12 is a top elevation thereof with the head of the light in the closed position;

FIG. 13 is a bottom elevation thereof;

FIG. 14 is a perspective view of a third embodiment of my novel design showing the head of the light in a horizontal position;

FIG. 15 is a perspective view of the embodiment of FIG. 14 showing the head of the light in the vertical position;

FIG. 16 is a front elevation thereof with the head of the light in the closed position;

FIG. 17 is a left side elevation thereof;

FIG. 18 is a top elevation thereof with the head of the light in the closed position; and

FIG. 19 is a bottom elevation thereof.

I claim:

The ornamental design for a pocket flashlight, as shown and described.
